UNITED STATES PATENT OFFICE.

WILLIAM F. OLIN, OF CHICAGO, ILLINOIS.

GRAIN-HARVESTER.

SPECIFICATION forming part of Letters Patent No. 368,964, dated August 30, 1887.

Application filed July 6, 1885. Serial No. 170,735. (No model.)

To all whom it may concern:

Be it known that I, WILLIAM F. OLIN, a citizen of the United States, residing at Chicago, in the county of Cook and State of Illinois, have invented certain new and useful improvements in Grain-Harvesters, which are fully set out in the following specification.

The purpose of this invention is to provide improved mechanism for transferring the grain from the delivery end of the sidewise-delivering platform conveyer of a harvester to the binder. It comprises the mechanism for advancing the grain sidewise from the platform conveyer toward the binder, the mechanism for moving the grain endwise and simultaneously evening the butts, both before and after the sidewise movement, and mechanism for adjusting the endwise-actuating mechanism, to adapt its action to the varying lengths of the grain, and thereby obviate the necessity for adjusting the binder back and forward for that purpose.

In the drawings, Figure 1 is a perspective, the point of view being the inner rear corner of the platform. Fig. 2 is a perspective from a slightly-different angle, and having the rear and upper parts removed to disclose the interior mechanism. Fig. 3 is a plan, and Fig. 4 is a rear elevation, of the sidewise and the endwise actuating mechanisms. Fig. 5 is a perspective detail of a piece which forms a bearing for the sickle, and has also a bearing for the vertical shaft of the inner endwise adjuster or butt-evener. Fig. 6 is a perspective detail of a vertical crank-shaft and its link-connection for adjusting the outer endwise actuating mechanism to long or short grain. Fig. 7 is a similar detail of the sliding yoke, which is actuated by the crank-shaft and carries the endwise-adjusting mechanism. Fig. 8 is a detail of a yoke and integral gear-wheel pertaining to the planetary gear system which actuates the endwise-adjusting mechanisms. Fig. 9 is a perspective of the bracket-box B² and the wheel B¹. Fig. 10 is a diagram to illustrate the action of the elevating and sidewise-actuating mechanism.

A is the platform, comprising the endless conveyer A¹, a ribbed belt or apron of the usual construction, carried by the roller A², which is journaled in the front and rear sills, A³ and A⁴, respectively. Upon these sills is

mounted the transverse conveyer and elevator B, hereinabove referred to as the "mechanism for advancing the grain sidewise" from the platform to the binder. Its construction is as follows: Upon the sills A³ and A⁴ are secured the bracket-boxes B' and B², respectively, the latter having rigid with it, concentric with its journal-bearing b², the fixed gear-wheel B¹. In these brackets is journaled the shaft B³, which receives motion from any convenient part of the driving-train of the harvester or binder by chain over the sprocket-wheel B³¹, fixed near its forward end. It has rigid with it the disk B³² inside or just in the rear of the front bearing, and the disk B³³ inside, in front of the fixed gear B¹ on the rear bearing. Upon suitable studs on the disk B³³ are journaled three gear-wheels, B⁴, arranged in a circle concentric with the shaft B³ and equidistant from each other, and all meshing with the fixed gear B¹. In a concentric circle outside that of the gear-wheels B⁴ are arranged six gear-wheels, B⁵, at equal intervals, and meshing two with each of the gears B⁴, and each fixed to and carrying a shaft, b⁶, which shafts extend through to and are journaled in the forward disk, B³². Each of the shafts b⁶ is provided with teeth b⁶¹, all on each shaft being in the same axial plane, and constituting, with the shaft, a revolving rake, as seen in Fig. 2.

To the platform-frame is secured the bracket-lip B', and to its upper edge are secured the strips B⁷, bent over between the teeth b⁶¹ in an arc inclosing the shafts b⁶ above and on the inner side, and extending down to a point about level with the axis of the roller A², and thence curved forward and upward, forming the trough b⁷¹, and all secured to the strip B⁷², a short distance from the end of the platform conveyer.

The binder-frame is supported on the main or platform frame, the supports being concealed from view in the drawings by the binder-deck. To the upper arm, C', of said binder-frame are secured the brackets D', and to their outer ends is secured the bar D, to which are secured the bracket D⁴ and the brackets D² 100 D². To the ends of the latter are pivoted the lugs D³¹, fixed on the board D³, which is also provided with the staple or loop D³², under which is inserted the arm D⁴¹ of the bracket

D⁴, thus furnishing the board D³ with three points of support from the bar D. Between the board D³ and the brackets D² D² are interposed the springs D²¹ D²¹, for a purpose hereinafter stated. The board D³ overhangs the transverse conveyer B, and is at a sufficient distance above it to allow the unobstructed revolution of the teeth b⁶¹ of the shafts b⁵.

E is the inner endwise adjuster. It comprises the vertical shaft E', stepped in the bearing e', which is provided in the bracket e, which is rigidly secured to the front sill, A³. The shaft E' has rigid with it the disk E¹¹ at the bottom and the disk E¹² near its upper end. Above the upper disk, E¹², the shaft is journaled in the bearing E²¹ of the yoke E². Said yoke has rigid with it about the bearing E²¹ the spur-wheel E²². On the lower side of said bearing and above said spur-wheel it has the annular boss E²³ about said bearing, and by means thereof it is itself journaled or pivoted in the end of the brace or horizontal bracket E³. Said bracket E³ extends and is secured rigidly to the bar D at e³⁴ and e³⁵, and is braced and rendered more rigid by the brace E³¹, as illustrated, but not necessarily. Said bracket is made in three pieces—viz., the arm E³⁰, the extension E³², at right angles with the part E³⁰, and the corner-piece E³⁴, which is fastened at 36 to both the other pieces, and affords the means of connection to the bar D at e³⁴, as stated, bolted to it at e³¹ and to the bar D at e³⁰.

On the upper surface of the upper disk, E¹², are journaled, upon suitable studs, two gear-wheels, E⁴ E⁴, meshing with the fixed spur-wheel E²² at opposite sides thereof, and outside of each of said gear-wheels E⁴ and in diametrical line with each other are provided in said disk journal-bearings for similar vertical shafts, e⁵ e⁵, carrying at their upper ends the gear-wheels E⁵ E⁵, and journaled at their lower ends in the lower disk, E¹¹. Said gear-wheels E⁵ E⁵ mesh with and are driven by the gear-wheels E⁴ E⁴, respectively. To the shafts e⁵ e⁵ are secured the vertical vanes or bats e⁵¹ e⁵¹, which are made rigid with the said shafts, respectively.

F is the outer endwise adjuster, similar in the construction and actuation of its constituent parts to the inner adjuster, E. The lower end of its shaft F' is journaled in the journal-box f' of the sliding yoke f, which has the journal-box f² for the packer-shaft N, on which it slides and by which it is sustained. The shaft F' has a shoulder to rest upon the shoulder f²¹ of the journal-box f' and sustain said shaft, and carries on its lower end, within the yoke f, the bevel-gear F⁶, which meshes with and is driven by the bevel-gear F⁷, feathered and adapted to slide on the shaft N. At the upper end the shaft F' is journaled in the yoke F², similar to the yoke E², and having above the rigid spur-wheel F²² an annular boss precisely like the boss E²³ on said similar yoke E², which constitutes its bearing in the slot e³² of the extension E³² of bracket E³. The yokes E² and F² have horizontal journal-boxes E²⁴

and F²⁴, respectively, in which the horizontal shaft G is journaled. Said shaft has at its outer end the bevel-gear G², meshing with and 70 driven by the bevel-gear F⁸, fixed on the upper end of the shaft F, and at its inner end the bevel-gear G¹, meshing with and driving the bevel-gear E⁸, fixed on the upper end of the shaft E'. The gear-wheel G² is feathered on 75 the shaft G and adapted thereby to slide on and revolve with it.

Upon any convenient fixed part of the frame in front of the transverse conveyer—as to the beam X—is fixed the vertical box H for the 80 crank-shaft H', which is provided with the crank H², from which extends the link H³ to the eye f³ of the sliding yoke f. The crank-shaft H' is provided with suitable stop, h, above the box H, and below said box has the coiled 85 spring H³⁰, stopped above by said box and below by the pin h', and tending to hold the said shaft H', with its stop h, down against the box H. Rigid with the shaft and with the crank H² is the notched segment H⁴, which is adapted 90 to engage the tooth or stud h⁴ on the top of the box H and detain the shaft H' and the crank H² and parts actuated thereby in any position to which they may be brought by revolving said shaft H', as may be done by means of the 95 crank-handle H⁵ at its upper end.

The crank H², stop h, and segment H⁴ are preferably made integral and afterward made rigid with the shaft by any convenient means, as the set-screw h⁶. 100

To the sliding yoke f is rigidly connected the rigid arm K, extending horizontally outward and forward to a point beyond the adjuster F, and bent upward at k, and to its upright portion K' is secured the butt-guard K². 105

The packers N¹⁰ are located in the usual position, and are actuated in the familiar manner by the cranks N¹¹, and strike up through the slots c c in the binder-deck C. Said slots c c, and hence the vertical planes of the packers, 110 are both located rearward from the outer butt-adjuster, as seen in Figs. 2 and 3.

I will now describe the operation of these devices.

First, the transverse conveyer B. The 115 revolution of its shaft B³, carrying the disks B²² and B²³, imparts to the gear-wheels B⁴ a revolution about their own axes by reason of their engagement with the fixed spur-wheel B²¹, said revolution being in the same 120 direction as that of the said disks. The gear-wheels B⁴ impart to the gear-wheels B⁵ a revolution about their respective axes in the reverse direction to the disks. The gear-wheels B⁵ are made equal in the number of their teeth 125 to the fixed spur-wheel B²¹, and hence make one revolution on their axes to each revolution of the disks on their axis, the shaft B³. Said revolution of the gear-wheels B⁵, being reverse in direction to that of the disks, causes 130 their axial planes to remain unchanged in direction, and their teeth b⁶¹ on their shafts b⁵ maintain an unvarying direction throughout the revolution of the disks. The said shafts

b⁶ have alternately vertical and horizontal teeth, three of them having their teeth horizontal and the alternating three having their teeth vertical. The horizontally-toothed rakes 5 enter under the grain as it is delivered into the trough b⁷ from the platform carrier and lift it, as they rise, with the disks, through the inner quarter of the revolution, and as they begin to withdraw within the circle of the strips 10 B⁷ the vertically-toothed rakes begin to protrude their teeth and enter the grain vertically from beneath, and carrying it over the upper quarter of the revolution and down onto the binder-deck, which is preferably about 15 midway from the level of the shaft B³ to the top of the curve of the strips B⁷. At this point the packers seize the grain; but with the succeeding steps in the process this invention is not concerned. As the grain is carried by 20 the rakes over the top quarter of the transverse conveyer, it enters under the board D³ and is thereby restrained and kept within the control of the rakes. If the grain accumulates on the outer side of the transverse conveyer B during the intervals of binding, the board B³ will be forced upward at its outer edge, turning on the pivots in the lugs D³¹ and compressing the springs D²¹ D²⁴.

Second, the endwise adjusters. The power 30 derived from the packer-shaft N drives first the outer, and from that, through the horizontal shaft G, the inner, endwise adjuster, F and E, respectively. The arrangement of the gearing is similar in effect to that which actuates 35 the transverse conveyer-rakes and gives to the vanes e⁵¹ and f⁵¹ an orbital motion about the shafts E' and F', respectively, and at the same time, by revolving them on their axes in the reverse direction, preserves their axial direction without change. This direction is substantially parallel to the vertical plane of the cut or at right angles to the axis of the transverse conveyer. Their motion is therefore forward against the butts of the grain and outward with its transverse or sidewise movement. The inner adjuster, E, stands forward of the line of the sickle, and the horizontal sweep of the vanes e⁵¹ extends close to the outer finger of the finger-bar, so that they attack 45 the grain at the heel of the sickle and prevent it from being obstructed at that point, and thrust it back endwise a distance sufficient to prevent the butts overhanging the forward end of the transverse conveyer B and move 50 the grain stubbleward with it past the sheath of the transverse conveyer and elevator B, as seen in Figs. 3 and 4. The outer endwise adjuster, F, acts upon the grain by a precisely similar movement, and thrusts it endwise such distance as may be necessary in order that the band may encircle it at the proper point in the length of the grain. Since the distance necessary to effect this result will vary with different lengths of grain, it is necessary to provide for moving the outer adjuster back and forward at will without interrupting its action. This is accomplished by the vertical crank-

shaft H' and its connections described with the sliding yoke f. When the grain is short, said shaft, being revolved to the right, will 70 slide the adjuster F to its extreme rear position, (illustrated in Fig. 4,) the yoke f sliding on the shaft N and causing the yoke F² to slide in the slot e³² of the portion E³² of the bracket E³, the shaft G sliding through the 75 gear-wheel G², the yokes E², F², and f retaining the gears which they respectively embrace properly in mesh through all variations of position. The butt-guard K², being secured to the yoke f, as described, moves with it, and 80 in all positions of the adjuster F corresponds accurately therewith.

I claim—

1. In combination with the platform conveyer, a series of horizontally-toothed rakes 85 and a series of vertically-toothed rakes, the individuals of one series alternating with those of the other series, and means whereby both are revolved without change of the direction of their teeth about an axis parallel 90 with the line of delivery of the conveyer, and the means of stripping the grain off said rakes, substantially as set forth.

2. In a harvesting-machine, in combination with the platform conveyer, a stationary 95 slotted deck at the delivery end thereof, convex upward, a series of horizontally-toothed rakes and a series of vertically-toothed rakes, the individuals of the one series alternating with the individuals of the other series, and 100 means whereby both are revolved without change in the direction of their teeth about an axis parallel with the line of delivery of the conveyer and within the curve of the said deck, and protruding their teeth through the slots 105 thereof, substantially as set forth.

3. In a harvesting-machine, in combination with the platform conveyer, a stationary slotted deck terminating in a horizontal lip adjacent to and lower than the carrying-surface of the conveyer, said deck extending thence upward and stubbleward, and a series 110 of horizontally-toothed rakes, and means whereby they are revolved without change of the direction of their teeth from a position below the said lip upward and stubbleward, and protruding their teeth through the slots in said deck, substantially as set forth.

4. In a harvesting-machine, in combination with the platform conveyer, a stationary 115 slotted deck at the delivery end thereof, convex upward, a system of planet-gears whose orbit plane is vertical, and whose axis is parallel with the line of delivery of the conveyer and is within the curve of said deck, the horizontal shafts of said planet-gears being armed 120 with rakes whose teeth protrude through the slots of said deck, said rakes being alternately provided with horizontal teeth and vertical teeth, substantially as set forth.

5. In a harvesting-machine, in combination with the sickle and the platform conveyer, the planet-gears whose orbit plane is horizontal, the fixed central gear having the same num- 130

ber of teeth as the planet-gear, and the bats on the vertical shafts of planet-gears, having their faces parallel with the vertical plane of the sickle, substantially as and for the purpose set forth.

5 6. In a harvesting-machine, in combination with the sickle and the platform conveyer, the planet-gear system whose orbit plane is horizontal and whose axis is forward of the vertical plane of the sickle, the fixed central gear having the same number of teeth as the planet-gear, and the bats fixed on the vertical shafts of said planet-gears, having their grain-actuating faces parallel with the vertical plane of the sickle, substantially as set forth.

10 7. In a harvesting-machine, in combination with the platform conveyer and the transverse conveyer at the delivery end thereof, an endwise-adjusting bat operating forward of the line of delivery of the platform conveyer, and means for controlling said bat to keep its grain-actuating face at all times parallel with the vertical plane of the sickle, to move said bat simultaneously rearward against the butts of the grain and stubbleward with its lateral flow, substantially as and for the purpose set forth.

15 8. In a harvesting-machine, in combination with the cutting mechanism and the sidewise-conveying mechanism, an endwise-adjusting bat and means for controlling said bat to keep its grain-actuating face at all times at the same angle to vertical plane of the cut, to move said bat simultaneously rearward against the butts of the prostrate grain and stubbleward with its sidewise flow, substantially as and for the purpose set forth.

20 9. In a harvesting-machine, in combination with the packers and the mechanism for delivering the grain sidewise thereto, an endwise-adjusting bat operating rearward from a point forward of the line of delivery of the sidewise-delivering mechanism, and means for controlling said bat to keep its grain-actuating face at all times at the same angle to the vertical plane of the cut, to move said bat simultaneously rearward against the butts and stubbleward toward the packers, substantially as and for the purpose set forth.

25 10. In a harvesting-machine, in combination with the platform conveyer and the transverse conveyer at the delivery end thereof, the inner planet-gears whose orbit plane is horizontal, the bats on the vertical shafts of said gears, and the fixed center gear of said system of planet-gears, having the same number of teeth as each of said gears, substantially as and for the purpose set forth.

30 11. In a harvesting-machine, in combination with the cutting mechanism and the sidewise-conveying mechanism, the inner system of planet-gears whose orbit plane is horizontal, a central fixed gear controlling the motion of said planet-gears and having the same number of teeth as each of said planet-gears, and bats fixed on the shafts of said planet-gears, having their grain-actuating faces parallel to the vertical plane of the movement of the side-

wise-conveying mechanism, substantially as set forth.

35 12. In a harvesting-machine, in combination with the binder-deck and the packer, the packers and the mechanism for delivering the grain sidewise thereto, the outer system of planet-gears whose orbit plane is horizontal, a central fixed gear having the same number of teeth as each of said planet-gears and controlling their motion, and bats fixed on the shafts of the planet-gears, having their grain-actuating faces parallel with the vertical plane of the movement of the sidewise-delivering mechanism, substantially as set forth.

40 13. In a harvesting-machine, in combination with the sickle and the platform conveyer in the rear thereof, the transverse conveyer at the delivery end of the platform conveyer, the binder deck and the packers operating at the delivery side of the transverse conveyer, a planet gear system whose orbit plane is horizontal and whose axis is forward of the vertical plane of the forward end of the transverse conveyer, and the bats fixed on the vertical shafts of said planet-gears, and a similar system of planet-gears similarly operating, having its axis located forward of the vertical plane of the foremost packer, substantially as and for the purpose set forth.

45 14. In a harvesting-machine, in combination with the packers and the mechanism for delivering the grain sidewise thereto, a system of planet-gears whose orbit plane is horizontal and whose axis is adjustable horizontally forward and backward, and the bats fixed on the vertical shafts of said planet-gears and facing the butts of the grain, substantially as and for the purpose set forth.

50 15. In a harvesting-machine, in combination with the mechanism for moving the grain sidewise, the planetary bat-actuating gear system and its vertical actuating-shaft, a horizontal shaft journaled on the frame, the sliding yoke journaled on said shaft and having a vertical bearing for the planet-gear-actuating shaft, the intermeshing bevel-gears on said shafts, respectively, the upper journal-box for the planet-gear-actuating shaft, having rigid with it the fixed controlling gear-wheel for said planet-gear system, and slide-bearings on the frame for said journal-box, and means for sliding said yoke and journal-box on their respective supports, substantially as set forth.

55 16. In combination with the planet gear system of the outer endwise butt-adjuster, the horizontal shaft which drives it and the sliding yoke journaled thereon, the yoke F², provided with a slide-bearing on the frame and adapted also to turn therein, and having rigid with it the controlling-gear of said planet-gear system, and having bearings for the actuating-shaft of said system, and a horizontal bearing for the shaft G, said shaft sliding through said bearing, the bevel-gear feathered on said shaft, and the bevel-gear on the planet-gear-actuating shaft meshing with and driving it, the planet-gear system of the inner endwise butt-

adjuster, the yoke rigid with its controlling-gear and having a horizontal bearing for the shaft, and the intermeshing bevel-gears on said shaft and on the actuating-shaft of said system, all operating substantially as and for the purpose set forth.

17. In a harvesting-machine, in combination with the platform conveyer and the transverse conveyer and elevator at the delivery end thereof, the endwise butt-adjusting bats hav-

ing the length upright as great as the height of the elevator, and in their lateral movement reaching stubbleward beyond the grain-stripping sheath of said elevator, substantially as set forth.
